UNITED STATES PATENT OFFICE.

JULES BREUCHAUD, OF NEW YORK, N. Y.

CONSTRUCTION OF SUPPORTS FOR WALLS, &c.

SPECIFICATION forming part of Letters Patent No. 570,870, dated October 27, 1896.

Application filed June 30, 1896. Serial No. 597,633. (No model.)

To all whom it may concern:

Be it known that I, JULES BREUCHAUD, a citizen of the United States, residing at New York, in the county of New York and State of New York, have invented new and useful Improvements in the Construction of Supports for Walls, &c., of which the following is a specification.

This invention has for its object to provide new and improved means for underpinning the wall of a building and forming either a temporary or permanent support for such building, or a subbase or foundation, temporary or permanent, for any heavy structure, the construction being such that the wall or other structure can be raised or lowered as occasion may require. To accomplish this object, my invention involves the features of construction, the combination or arrangement of parts, and the principles of operation hereinafter described and claimed, reference being made to the accompanying drawings, in which—

Figure 1 is a detail sectional view showing a portion of a building-wall and the manner of applying hydraulic jacks according to my invention to drive hollow columns at opposite sides of the wall for the purpose of supporting the wall temporarily or permanently. Fig. 2 is a similar view showing the manner of supporting the wall by the two sets of columns driven by opposite sides of the wall. Fig. 3 is a detail plan view. Fig. 4 is a detail vertical sectional view showing a portion of a wall supported by the two sets of columns in such manner as to permit alteration in or reconstruction of the lower portion of the wall. Fig. 5 is a detail view of the arrangement shown in Fig. 4. Fig. 6 is a detail vertical sectional view showing a modification of my invention, and Fig. 7 is a detail sectional view showing the manner in which a subbase or foundation is provided beneath an old wall for the purpose of supporting a new wall or other structure built next the old one.

In order to enable those skilled in the art to make and use my invention, I will now describe the same in detail, referring to the drawings, wherein—

The numeral 1 indicates the wall of a building or other heavy structure which is to be underpinned or provided with a subbase or

foundation, either temporary or permanent, according to my invention.

The wall indicated in the figures of the drawings is designed to represent the wall of any building already erected which is to be underpinned or provided with a permanent subbase or foundation, or which is to be supported while it is altered or reconstructed in its lower portion. The wall may, however, be any high or tall or heavy structure other than the wall of a building.

In carrying my invention into effect I insert a beam 2 transversely into the lower portion of the wall 1, so that the beam projects at its ends from the opposite sides of the wall in such manner that these projecting ends constitute abutments for hydraulic jacks 3 and 4, also located at opposite sides of the wall. The hydraulic jacks are designed to drive tubular sectional columns 5 and 6 into the ground for the purpose of placing at each side of the wall 1 a series of tubular columns, which may be utilized for permanently or temporarily supporting the wall, or partly as a subbase or foundation for a new wall or other structure erected beside the old wall or already-erected building or other object.

The tubular columns are preferably composed of iron, but they may be made of any metal suitable for the purpose, and are composed of a plurality of cylindrical sections adapted to be successively driven into the ground through the medium of the hydraulic jacks. In driving the columns the first sections are placed under and in alinement with the jacks, and the latter are operated to drive these sections perpendicularly into the earth. The next sections are attached to the upper ends of the first driven sections, and the second sections are operated by the jacks and also driven perpendicularly into the earth. These operations are proceeded with until the number of sections constituting the columns are driven to the depth necessary to reach bed-rock or other firm strata. During the driving of the sections composing the tubular columns the transverse beam 2 bears the superincumbent weight of the building-wall and resists the pressure of the jacks, whereby the latter may exert a very powerful force in driving or sinking the columns section by section in the manner described.

In order to prevent the wall from cracking, splitting, or otherwise rupturing during the operation of driving or sinking the columns, I arrange in the wall the longitudinal iron or other beams or girders 7, against which the transverse beam 2 bears. Any desired number of beams or girders 7 may be arranged in the wall, but in the drawings I have represented four beams of I shape in cross-section, 10 although they may be of any desired form.

The hydraulic jacks may be utilized in the arrangement shown for raising or lowering the wall to any required extent.

After two or more columns have been driven 15 at opposite sides of the wall the transverse beam may be placed, as at 8, Fig. 2, upon the upper ends of the columns and built upon for the purpose of perfecting the old wall, and thus placing beneath it a permanent sub-base or foundation, as will be readily understood, or a beam, as at 9, may be placed on the upper ends of the columns and constitute a support for uprights 10, Figs. 4 and 5, bearing against longitudinal beams or girders 12, 25 inserted into the old wall or other structure, so that the latter can be sustained during the time that any alteration is made therein or while the lower portion of the wall is being reconstructed or repaired. The uprights 10 30 may be iron posts of any desired shape in cross-section and their upper ends may bear against plates 13, which abut the longitudinal beams or girders 12.

In the modification, Fig. 6, a transverse beam 14 is inserted at one end into or 35 through the wall 1, and at the other end may be provided with a heavy weight, as at 15. The weight 15, if used, is preferably arranged on a support 16, suspended from the beam 14 40 by a suspending-rod 17 or other device. The hydraulic jack 18 operates against the beam 14 in juxtaposition to the building-wall 1, for the purpose of driving the tubular columns 19 perpendicularly into the earth. The columns 19 are made the same as the columns heretofore described; that is, each is composed of sections which are successively 45 driven or sunk by the jack.

In Fig. 7 is represented the manner in which 50 a transverse beam 20 is supported by tubular columns driven or sunk into the earth at one side of the wall 1 through the medium of the hydraulic jacks, as hereinbefore explained. In this arrangement the beam 20 and tubular 55 columns at one side of the wall of the old or already-erected building constitute a base or foundation for the erection of a new building-wall or other structure.

In Fig. 3 is represented in plan view the 60 longitudinal beams or girders 7, against which the transverse beams 8, Fig. 2, bear to support an existing wall.

The arrangement shown in Fig. 6 is advantageous and useful for driving the columns at one side of any structure for forming a foundation close to such structure to erect another building or other object.

In the present invention the fulcrum against which the hydraulic jacks work is the transverse beam, one or more, inserted into the 70 wall and having their projecting end or ends acted upon by the jacks. The transverse beam, one or more, is resisted in upward motion by the superincumbent weight of the existing wall or other structure. 75

The transverse beam 2, one or more, may bear directly against the masonry of the wall or other structure, but it is advisable to have the beam, one or more, bear against the longitudinal beams or girders 7, inserted into the 80 wall, as hereinbefore explained.

It will be evident that while the old wall or other structure is supported by the jacks it can be extended downward to any required depth without danger of the building or any 85 part of the same collapsing. It will also be observed that by placing the posts 10 on the beam 9, one or more, the wall 1 can be supported at any desired height above the foundation, thereby permitting any alteration in 90 or reconstruction of the lower portion of the wall.

Having thus described my invention, what I claim is—

1. The method herein described of constructing a foundation for a building-wall, or other structure, which consists in inserting a beam transversely into the wall, or other structure, arranging hydraulic jacks in engagement with said beam outside the 100 vertical plane of the wall and successively driving column-sections perpendicularly into the earth until a column is formed which reaches bed-rock, or other firm substrata, substantially as described. 105

2. The combination with a building-wall, or other structure, of a beam inserted transversely into the wall and projecting laterally therefrom, and a hydraulic jack engaged with the laterally-projecting end of the beam and arranged perpendicularly to successively drive the sections of tubular columns into the earth until a column is formed which reaches bed-rock, or other firm substrata, substantially as described. 110

3. The combination with a building-wall, or other structure, of a beam inserted transversely into the wall and having its ends projecting from opposite sides thereof, and hydraulic jacks arranged at opposite sides of the wall, or other structure, and engaged with the projecting ends of said beam to successively drive column-sections perpendicularly into the earth until columns are produced which reach bed-rock, or other strata, 120 and are located at opposite sides of the wall or other structure, substantially as described. 125

In testimony whereof I have hereunto set my hand in presence of two subscribing witnesses.

JULES BREUCHAUD.
